UNITED STATES PATENT OFFICE.

LOUIS J. STERN, OF NEW YORK, N. Y.

DESIGN FOR A LIQUID CONTAINER.

Application filed March 9, 1929. Serial No. 30,394. Term of patent 14 years.

To all whom it may concern:

Be it known that I, LOUIS J. STERN, a citizen of the United States, residing at New York city, county of New York, borough of Manhattan, and State of New York, have invented a new, original, and ornamental Design for Liquid Containers, of which the following is a specification, reference being had to the accompanying drawing, forming part thereof.

The figure is a perspective view of a liquid container, showing my new design.

I claim:

The ornamental design for a liquid container, as shown.

LOUIS J. STERN.
